(57) **CLAIM**

We claim the ornamental design for a shower device, as shown and described.

DESCRIPTION

This application is related to application Ser. No. 29/415, 587, filed Mar. 12, 2012, entitled "Shower Faceplate", to application Ser. No. 29/450,323, filed Mar. 16, 2013, entitled Shower Faceplate and Shower Device, and to application Ser. No. 29/450,310, filed Mar. 15, 2013, entitled Shower Faceplate and Shower Device, the entire contents of all of which are hereby incorporated by reference.

FIG. 1 is a front view of the shower device, such as a showerhead; and,

FIG. 2 is a perspective view of the shower device shown in FIG. 1.

One or more side and/or bottom views of a shower device are mirror images of another view and, therefore, have been omitted.

Any broken line showing of the environment is for illustrative purposes only and forms no part of the claimed design.
